UNITED STATES PATENT OFFICE.

ERNEST J. LANGHAM, OF JOHNSTOWN, PENNSYLVANIA.

SHORING DEVICE.

Application filed May 12, 1925. Serial No. 29,812.

The principal object of this invention is to provide a novel and improved shoring device including means whereby the device may be collapsed for removal and re-use at 5 a different point.

Another object of the invention is to provide an extremely durable and easily manufactured shoring device particularly adapted for use in mines for supporting the ceiling during excavating operations, the device having means facilitating its removal after the mining operation has been completed for use in further operations.

In the attached drawings:

15 Figure 1 is a side elevation of a device made in accordance with my invention;

Fig. 2 is a view in perspective of one of the main parts of the device;

20 Fig. 3 is a view in perspective of the intermediate or wedge section;

Fig. 4 is a detached perspective of the bolt or holding means for the intermediate section, and

25 Fig. 5 is a view in perspective of the bearing plate.

With reference to the drawings, the device comprises a base section 1 flanged at the bottom to provide a suitable base 2 and a like top section 3 similarly flanged at the 30 top to provide a suitable extended bearing surface at that end. The upper end of the bottom section 1 and the lower end of the upper section 3 are oppositely inclined, as clearly illustrated, and an intermediate 35 wedge-shaped member 4 is provided for insertion between the bottom and top sections and adapted to form with said sections a substantially straight-sided post having the aforescribed flanges at top and bottom. 40 As clearly illustrated, both the top and lower sections are provided on their inclined faces with a central channel or groove 5 of uniform depth, said channel extending from one side of the section to the other, and these channels 5 form guideways for tongues 6, 6, on the opposite inclined faces of the intermediate section 4. As will be apparent, 45 these coacting tongues and grooves prevent transverse displacement of the intermediate section with respect to the others.

In order to secure the wedge-shaped intermediate section 4 in the assembled position, as shown in the drawings, I provide a bolt 7 which extends completely through the intermediate section 4, a rectangular counter-

sunk recess 8 being provided at the back of the section for the correspondingly shaped head 9 of said bolt. A locking member 10 also is provided with a central opening 11 for the bolt 7, and this member preferably is no greater in width than the smaller side of the wedge-shaped intermediate member 4, and the member 10 further is preferably tapered outwardly so that in one position it constitutes in effect a prolongation of the 65 said wedge 4, as illustrated in Fig. 1. The member 10 further is of greater length than width so that when turned so as to lie longitudinally of the assembled post, as shown in Fig. 1, it overlies the top and bottom 70 sections, and thereby, when the nut 12 is tightened in back of the member, prevents withdrawal of the intermediate section. With this construction, it will be apparent that the bolt 7 also provides, by turning of 75 the nut 12, for forcing the intermediate wedge-shaped member 4 between the outer sections 1 and 3 whereby the latter are forced apart.

It is preferable to tie all the elements of 80 the shoring post together when not in use, in order that none of the parts will be missing when it is desired to re-assemble the shoring post; for this purpose the sections 1 and 3 are each provided at each of their 85 sides with an eye bolt 15 and 16 respectively, to which are connected the opposite ends of a chain 17. The intermediate section 4 is provided at each side with an elongated eye 18 through which the chain 17 passes. 90 The bolt 7 remains in the intermediate section 4 and the locking element 10 and nut 12 remain on the bolt 7; thus all the elements of the shoring post are retained in a group.

In setting up this device, the small end of 95 the intermediate section 4 is inserted between the sections 1 and 3, with the locking member 10 turned horizontally and having its tapered sides contiguous with the tapered sides of the section 4, the element 10 being 100 positioned adjacent the front or narrow edge thereof when it is inserted between the elements 1 and 3, and when the member 10 is turned into the position illustrated in Fig. 1, the nut 12 is turned inwardly on the bolt 105 7 to thereby force the intermediate section between the others and to spread the latter.

Where the device is employed to shore the roof of a mine digging, the flange 2 may rest upon the floor or upon any suitable pedestal. 110

2
built up on the floor and the upper end brought to bear against the roof or against beams underlying the roof. The nut 12 is then tightened to bring the wedge approximately into the position shown in the drawings, the upper and lower sections during this operation being forced away from each other and tightly against the support and the overhead bearing. When it is desired to remove the device, it is only necessary to release the nut 12 and to turn the member 10 to a horizontal position which permits it to slide between the top and bottom sections. The wedge-shaped intermediate part may then be easily displaced and the device removed for a further operation.

Obviously there may be considerable modification without departure from the essential features of the invention.

3. I claim:

1. A shoring device comprising upper and lower sections having oppositely inclined adjacent ends, a substantially wedge-shaped intermediate element adapted for insertion between the upper and lower sections and to form therewith a rigid post, and means including a bolt extending through said intermediate section and supporting a member at the narrow edge of the latter adapted to be passed between the upper and lower sections when in one position and when turned at right angles thereto to overlap the said upper and lower sections for detachably retaining the intermediate section in position between the said upper and lower sections.

2. A shoring device comprising upper and lower sections having their adjacent faces oppositely inclined, an intermediate substantially wedge-shaped section adapted for insertion between the said upper and lower sections to form therewith a rigid post, a retaining bolt extending through said intermediate section and having at the narrow side of said section a retaining member whose width is no greater than the width of the said narrow end of the intermediate section when in a position adapted for passage therewith between said upper and lower sections and whose length is sufficient to overlap the upper and lower sections when in a position longitudinally of the post, and a nut on the bolt adapted to bear against said member to retain the intermediate section in

position between the upper and lower sections.

3. A shoring device comprising upper and lower sections having their adjacent faces oppositely inclined, an intermediate substantially wedge-shaped member adapted for insertion between the inclined faces of the upper and lower sections to form with the latter a rigid post, a bolt extending through the intermediate section from the small side to the large and supporting on said small side a member whose maximum width is no greater than the width of the small side of said wedge-shaped intermediate section, said member being tapered outwardly in conformity to the taper of said wedge-shaped section so as to constitute in effect an extension of the latter for passage therewith between said upper and lower section, and said member also being of sufficient length to overlap the upper and lower sections when in a position longitudinally of the device, and a nut on said bolt adapted to bear against the said member to retain the intermediate section in position between the others.

4. A shoring device comprising upper and lower sections having their adjacent faces oppositely inclined, an intermediate substantially wedge-shaped member adapted for insertion between the inclined faces of the upper and lower sections to form with the latter a rigid post, a bolt extending through the intermediate section from the small side to the large and supporting on said small side a member whose maximum width is no greater than the width of the small side of said wedge-shaped intermediate section, said member being tapered outwardly in conformity to the taper of said wedge-shaped section so as to constitute in effect an extension of the latter for passage therewith between said upper and lower sections, and said member also being of sufficient length to overlap the upper and lower sections when in a position longitudinally of the device, and a nut on said bolt adapted to bear against the said member to retain the intermediate section in position between the others, and means for tying all the elements of the shoring device together when said shoring device is not in use.

ERNEST J. LANGHAM.
